UNITED STATES PATENT OFFICE.

ROBERT E. MARTIN, OF CROZET, VIRGINIA.

FRUIT-PACKING DEVICE.

Application filed October 18, 1926. Serial No. 142,338.

This invention relates in general to a device for packing fruit, and more particularly to an apparatus for assembling a fruit container, and subsequently packing the fruit when placed therein.

An object of this invention is to provide a suitable apparatus for placing and maintaining the ends of the container in the correct position for accurate attachment to the body of the container in the operation of assembling the container.

Another object of my invention is to provide such apparatus that will also be suitable for pressing the fruit when placed in the container.

A further object is to provide the device with a novel system of levers and swinging supports whereby the device may be rendered readily operable throughout the various stages of the assembling and packing operations.

Another object is to provide a novel type of container which will permit of ready assembling.

With the foregoing and other objects in view, the invention consists in the combination of parts and in the details of construction hereinafter set forth in the specification certain embodiments being illustrated in the accompanying drawings, in which:

Fig. 1 is a view in front elevation of the device with the container placed over the frame in position for assembling the container.

Fig. 2 is a view in side elevation of the same as Fig. 1.

Fig. 3 is a top plan view of the same as Figs. 1 and 2.

Fig. 4 is a fragmentary view of the device in front elevation, showing the frame over which the body of the container may be placed for assembling the container.

Fig. 5 is a top plan view of the plunger.

Fig. 6 is a section through the plunger and the smaller end of the basket taken along line 6-6 of Fig. 5.

Fig. 7 is a front elevation in perspective of the assembled container.

Referring more particularly to the drawings, 1 is a platform supported by a pair of front legs 2 and a pair of rear legs 3. Pivotedly connected at 4' and 7' are a pair of uprights 4 and 7 capable of backward and forward pivotal movement which latter is limited by a pair of guides 5 slidable on studs

6 attached to the legs 3. Hingedly attached at 8' to the upright 4 is a crossbar 8 which extends through a vertical slot in the upright 7, whereby the movement of the crossbar is both guided and limited. Pivotedly attached at 9' is a plunger rod 9, to which is connected a circular plunger 10 of resilient metal having a plurality of cleats 11 throughout its periphery and pivotally attached thereto at 12 so that the position of the cleats may be varied for the desired purpose.

Suitably attached at 13' to the crossbar 8 is a vertical arm 13, the latter being pivotally connected at 14' to a hand lever 14 which is pivotally connected at one end to one of the legs 3 at 15. The hand lever 14 has a lug 16 adapted to engage the various notches of a plate 17 which is attached to one of the front legs 2. A tension spring 18 is extended between and connected to the arm 13 and the hand lever 14 in such a manner and at such points that release of the lug 16 from the notches in the plate 17 results in the spring 18 returning the hand lever to its normal upward position and the raising of the plunger 10.

Fig. 4 shows the platform 1 with a skeleton frame supported thereon. This frame has a large end 19 which is placed on the platform, and a small end 20 with pieces 21 extending between the two ends. The purpose of this frame is to aid materially in the assembling of the fruit container.

In actual operation the body 22 of the empty container is placed over the frame when the latter is in the position shown in Fig. 4. The small end 24 of the container, having cross strips 25, is then introduced into the body 22, until the end 24 rests on the top 20 of the frame. The relative heights of the container body and the frame are such that the smaller end 24 is now in correct position to be affixed to the container body. To securely maintain this relative position, the hand lever 14 is pushed downwardly. This action, by means of the system of levers previously explained, causes the plunger 10 to engage the small end 24 and hold it against the frame top 20 under pressure. The cleats 11, being swung into the position shown in Fig. 1, fit over the edges of both the end 24 and the adjacent edge of the body 22, thus aiding in maintaining the proper relative positions for fastening.

The body 22 has a plurality of clips 23

which are bent around the edge of the end 24 which holds the latter in assembled position.

The container is then turned with the large 5 end up and filled with fruit, or the like in any approved manner. A cover 26 is then placed on the container and the pieces 27, which form a part of the cover are passed through clips 28, whereby the cover may be secured to 10 the large end of the container.

The frame is then removed from the platform 1 which may have a hole cut therein approximately the size of the small end of the container. The full container is placed with 15 the large end resting on the platform over the hole. The plunger 10 is then swung into position on the cover 24 and pressure applied thereon by pushing down on the hand lever 14. In this manner the fruit is pressed, 20 the hole in the platform allowing for any bulge in the cover over the large end of the container. The cleats 11 are obviously placed over the edges of the cover 24 and the small end of the body of the container, this 25 manual operation being the same as takes place in the assembling of the cover 24. The fact that the uprights 4 and 7 are pivoted at 4' and 7' makes it easily possible to place and withdraw the container and frame 30 upon and away from the platform throughout the assembling, packing, and pressing operations.

I claim:

1. In a device for assembling the ends of a

container, and packing and pressing same 35 and its contents, said device comprising a platform and a removable frame supported thereby and of substantially the same contour as the container, a manually and positively operated resilient pressure member 40 adapted to maintain the component parts of said container in position upon said frame for assembly, and subsequently after the removal of the frame, the reversal of, and the filling of said container adapted to be applied thereto for pressing said container and its contents.

2. In a device for assembling the ends of a container, and packing and pressing same 50 and its contents, said device comprising a platform and a removable frame supported thereby and of substantially the same contour as the container, a manually and positively operated resilient pressure member 55 adapted to maintain the component parts of said container in position upon said frame for assembly, and subsequently after the removal of the frame, the reversal of, and the filling of said container adapted to be applied thereto for pressing said container and 60 its contents, said pressure member comprising a resilient ring with angular cleats pivoted thereto and adapted to fit over the edges of the container body and cover both in the 65 assembling and pressing operations.

In testimony whereof I affix my signature.

ROBERT E. MARTIN.
